UNITED STATES PATENT OFFICE.

ALEXANDER W. MCNEIL, OF CHICAGO, ILLINOIS.

DESIGN FOR AN INKSTAND.

SPECIFICATION forming part of Design No. 22,773, dated September 12, 1893.

Application filed March 6, 1893. Serial No. 464,906. Term of patent 3½ years.

To all whom it may concern:

Be it known that I, ALEXANDER W. MCNEIL, a subject of the Queen of England, residing at Chicago, in the county of Cook and 5 State of Illinois, have invented and produced a new and original Design for Inkstands, of which the following is a specification, reference being had to the accompanying drawings, shown as a part thereof.

10 In the accompanying drawings Figure 1 represents an elevation of my design and Fig. 2 represents the plan of the same.

The leading features of my design consist of a model of the northern hemisphere provided with a beveled rim or base and on the 15 top of said hemisphere the model of an egg having on it a figure of Columbus. The hemisphere has on it the map of the countries belonging to it and on said map is traced a line representing the course taken by Columbus on his first voyage to America. On the 20 side of said hemisphere is a step like rack.

In the drawings A represents the hemisphere with the outline of the countries on it and a representation of the latitudinal and 25 longitudinal lines. At the bottom of the hemisphere is placed the base B. On the top of this hemisphere rests the model of an egg C. The ink receptacle is placed in the hemisphere. The step like rack E is placed upon 30 the side of the hemisphere as illustrated in the drawings.

Having thus described my design, what I claim as new, and desire to secure by Letters Patent, is—

35 The design for an ink-stand substantially as shown and described.

ALEXANDER W. MCNEIL.
